THEODORE J. SCOFIELD, LLOYD E. JOHNSON, FRED W. BILLIG, AND WILLIAM SPARKS, OF JACKSON, MICHIGAN, ASSIGNEES TO THE SPARKS-WITHINGTON COMPANY, OF JACKSON, MICHIGAN, A CORPORATION OF OHIO

SIGNALING DEVICE

Application filed July 15, 1927. Serial No. 205,937.

This invention relates to certain new and useful improvements in signaling devices.

It is found in the use of air horns of the character herein illustrated that when two or more sound-producing devices are utilized for the production of preferably harmonious notes that the resultant sound is of excellent carrying quality and can be heard long distances in open spaces, but the sound lacks somewhat the desired capacity of penetrating enclosed chambers, such as the closed body of an automobile, due perhaps to the fact that sufficient air is not driven into the projectors when a plurality of the same are utilized by a power plant of the size and weight adapted for use on automobiles or other vehicles, and the object of this invention is to provide an air horn of the character illustrated, utilizing two or more sound-producing devices, and in which means is provided for permitting the use of either one or of two or more such sound producing devices, dependent upon the character of the note or notes which it is desired the device should emit, whereby all of the air moved under pressure by the pressure-producing device is forced through one of the sound-producing devices to provide a sound of sufficient amplitude and penetrating character so that persons within a closed chamber or vehicle readily hear the sound, or where it is desired to advise persons on the open road of the approach of the vehicle, the air column may be divided and directed through two or more sound-producing devices, thereby producing a preferably harmonious note or notes having the desired capacity for warning the public to be advised of the approach of the vehicle.

And the object of this invention resides in the production of a signaling device having the capacity of utilizing one or more sound producing devices so that all of the air may be forced through one of such devices to produce a desired sound or through two or more of such devices to produce a sound desired under other conditions and circumstances.

Other objects and advantages relate to the details of the structure and the form, relation and operation of the parts thereof, all

as will more fully appear from the following description, taken in connection with the accompanying drawings in which:

Figure 1 is an elevation of a device of this invention.

Figure 2 is a section on line 2—2, Figure 1.

Figure 3 is a section on line 3—3, Figure 1.

Figure 4 is a section on line 4—4, Figure 1.

Figure 5 is a section similar to the upper portion of Figure 2 illustrating the use of more than two sound-producing devices.

Figure 6 is a section similar to the upper portion of Figure 2, of a modified form of device in which a manually actuated valve is used.

Figure 7 is a section on line 7—7, Figure 6.

Figure 8 is a section on line 8—8, Figure 6.

The structure as herein illustrated consists of a rotary electric-motor —1— having its armature shaft substantially vertically disposed, and the upper end wall —2— of the case of the motor is of substantially circular form, and provided with a depending tubular boss —3—, in which the upper end of the armature shaft —4— is journaled.

The lower end of the armature shaft —4— extends through an opening in the U-shaped case —7— and may be provided with an adjustable bearing —5— carried by the end or cross-wall —6— of the U-shaped motor-case —7—. The ends of the U-shaped motor case —7— are secured to the flanges —8— and —9— respectively formed upon the upper end wall —2—. The usual armature —10—, pole pieces —11— and field coils —12— are provided.

The actual structure of the motor may vary widely, the essential being a means for producing rotary movement, and any form of electric motor may be utilized which is capable of driving a rotary compressor which constitutes a portion of the device, and for this purpose the end wall or head —2— is formed with a circular chamber or cylinder —14— on the side opposite the electric motor —1—, and this cylindrical recess or chamber is eccentric with respect to the armature shaft —4— and to the rotor shaft —15— which is aligned with the armature shaft —4—, and may be connected to the rotor —13— in any

55

100

suitable manner, as for instance formed integrally with the rotor.

The rotor shaft extends into and is journaled in the boss —3— and may terminate a short distance above the upper end of the armature shaft —4—, and is connected to the armature shaft for simultaneous rotary movement while permitting relative longitudinal movement in any suitable manner, as by a key —50— extending into slots formed in the adjacent ends of the rotary shaft, and the armature shaft for locking the two against relative rotary movement, the key being positioned at an intermediate point along the bearing —3—.

In effect, the rotor shaft —15— and the armature shaft —4— are a sectional armature shaft and for the purpose of the claims of this application may be so considered.

20 The armature shaft being concentric with the end head —2— and the rotor —13— being concentric with the armature shaft, the rotor is eccentrically positioned in the cylinder or chamber —14— by reason of the 25 fact that the said cylinder is formed eccentrically in the end head.

The end head —2— is further formed with an air storage chamber —17—, in this instance arranged concentrically with the wall 30 of the cylindrical chamber —14— and extending around the cylindrical chamber throughout slightly more than one-half of its circumference. This storage chamber is in communication with the pressure side of the rotary 35 pump through a port —18— in the wall of the chamber —14—, and through this port air under pressure is ejected by the rotor —13— from the chamber —14— and for effecting this result the rotor —13— includes 40 one or more, in this instance three movable blades —19— slidably mounted in grooves or recesses in the rotor, and preferably spaced equal distances apart, and adapted to be thrown out by centrifugal force as the 45 rotor —13— is driven by the armature shaft —4—.

The compressor chamber —14— is formed with an air inlet —20— at the suction side of the compressor, and which air inlet penetrates the bottom wall of the compressor chamber, and leads into the casing —51— which encloses the electric motor —1—. This casing is usually imperforate and for the purpose of admitting air to its interior, 55 it is formed with a struck-up portion —52— interrupting the continuity of the casing wall and forming a passageway whereby air may be freely supplied to the inlet —20— of the compressor and without the production of 60 vacuum within the casing —51—.

Mounted upon the upper end of the head —2— and covering the compressor chamber —14— and the storage chamber —17— is a horn body —56— secured to the head —2— 65 in any suitable manner, as by screws —57—,

and suitable packing may be interposed between the body and the head to prevent the escape of air when compressed.

The body —56— is formed at one side with a vertical conduit —58— leading to two lateral conduits —100— and —101—, and normally communication is cut off between the two conduits —100— and —101— by a valve —102— seating against the tapered inner end of a core —103— of an electromagnet —104—, and the end of the stem 105 of valve 102 is connected to the armature 106 of the electromagnet 104 and the rear end of the core 103 is recessed for the reception of a spring 107 seating against the inner end of the recess and against the forward side of the armature 106 to normally maintain the armature spaced from the rear flanged end 108 of the core 103. The coil 109 may be enclosed between the outer surface of the core 103 80 and a cup shape casing 110.

85 The electromagnet is secured to the horn body —56— by having the front end of the core inserted in an opening in the horn body, which opening is in communication with the 90 passageways 100 and 101, the inner end of the core seating against the flanged portion of the wall surrounding said opening, and the core may be formed with an annular flange 111 against which the inner end of a 95 nut 112 is adapted to press when the nut is threaded into the interiorly threaded wall 113 which surrounds the opening in the body into which the core is inserted. In this manner a rigid and substantial support for the 100 electromagnet, the valve and its operating structure is provided.

A cap —114— preferably covers the armature 106 and may be secured to the wall of the cup-shape casing 110.

105 In Figures 1, 2 and 3 two separate sound-producing devices are utilized, and except for the length of the projectors —60— these sound-producing devices are of similar form. One of them is in communication with the 110 passageway 100 and the other is in communication with a passageway 101 and under normal conditions all of the air under pressure moving from the storage chamber 17 will pass to the sound-producing device in 115 constant communication with the passageways 58 and 100.

However, when the electromagnet 104 is energized by connecting it in circuit with a suitable source of potential as the battery 120 of an automobile, a suitable switch being provided, the armature 106 will be drawn toward the coil 109 and toward the flanged end 108 of the core 103 so as to open valve 102 to permit the passage of a portion of the air from the storage chamber through passageways 58, 100 and 101 to the other sound producing structure, under which circumstances two notes preferably of harmonious character, are simultaneously produced. 125 130

A description of one of the sound producing devices will constitute a description of both.

The projectors —60— differ in this illustration in that one of them is somewhat longer than the other for the purpose of producing different notes which by suitable adjustment of the devices can be made harmonious in character.

10 In each case the projector —60— has its rear end threaded into the front end of one of the bosses —59— on the horn body and a tube —61— is threaded into the boss so as to substantially contact with the rear end 15 of the projector —60—, and this tube projects rearwardly from the boss —59—.

Each boss —59— has a circumferentially enlarged intermediate portion forming an annular chamber —62— surrounding the tube 20 —61— and in communication with the respective conduits —58—. The rear end of each boss is internally enlarged with respect to the front end and is threaded for the reception of an externally threaded tubular 25 boss —63— formed concentrically at the base of a cup-shaped member —64— which may be locked in any desired position with respect to boss —59— by means of lock nut —65—.

30 The internal diameter of the boss —63— is somewhat greater than the external diameter of the tube —61— so as to form an annular passageway around the tube leading from chamber —62— to the interior of the cup 35 shape member —64—. The external wall of the cup-shape member —64— is externally threaded for cooperative engagement with the interiorly threaded flange upon a cup-shape cap —66— and this cap —66— is 40 formed with a radial shoulder —67— between which and the end of the cup-shape member —64— a thin metallic diaphragm —68— has its edge confined.

The size and arrangement of the parts is 45 such that when the diaphragm is positioned, as described, it extends across and normally closes the rear open end of the tube —61— and preferably the rear open end of tube —61— is flared, as indicated at —69—.

50 It is found that the air in the chamber between the diaphragm —68— and the cap —66— varies in pressure somewhat in accordance with the temperature to which the device is subjected, thereby varying the pressure upon the diaphragm —68— which in 55 turn effects the operation of the signaling device, and in order to maintain the device uniform in operation, the cap —66— is provided with one or more openings —70— leading to the chamber between the diaphragm —68— and the cap to permit the entrance of air to or the exit of air from said chamber to maintain a normal pressure, irrespective of temperature changes.

60 These openings may, if desired, be cov-

ered on the inside by plate —71— and on the outside by disk —72— for appearance sake so long as sufficient space is provided, as for instance by small grooves or passageways 73 for the escape or entrance of air.

70 In operation, when the armature shaft is rotated, air entering through inlet —20— is compressed and ejected through outlet —18— into the storage chamber —17— and thence passes through conduit —58— to the sound-producing device in constant communication therewith, and with the passageway 100. By closing the switch in the circuit leading to the coil 104 valve 102 will be opened to permit a proportional quantity of air to pass to the sound-producing devices in constant communication with the passageway 101 so that by the utilization of this structure all the compressed air may be supplied to one sound producing device to produce a note 80 of great amplitude and penetrating power, or the air column may be divided and a proportionate amount applied to each sound producing device to produce two notes, preferably of a harmonious character.

85 Figure 5 illustrates a similar structure except that a third sound-producing device is utilized which may produce a third note of harmonious character and may have a projector of different length from the other two projectors 60, and in this structure the horn body 56 is provided with a tubular extension 117 having at its upper end a boss 118 similar to the bosses 59 and carrying a third sound producing device of identical structure 90 with the two sound producing devices heretofore described.

95 Tubular passageway 117 is at all times in communication with the passageway 101 so that when the second sound producing device is actuated upon opening of valve 102, the third sound producing device will be simultaneously actuated.

100 It will be obvious that a number of sound producing devices may be utilized with one or more valves positioned as described, and suitably actuated to permit the passage of air to any one or all of said devices.

105 Figures 6, 7 and 8 illustrate a modified form of structure in that the valve for controlling communication between the storage chamber 17 and one of the sound producing devices is controlled by a manually actuated valve. As illustrated in these latter figures, 110 two sound producing devices of similar construction are disclosed, and these devices are of the same construction as those described in connection with the former figures, altho the projector 118 may, as before, be somewhat larger than the projector 119.

115 In this illustration, the horn body 56 is formed with two passageways 120 and 121 leading from the storage chamber 17 to the respective sound producing devices, and to the spaces within the respective bosses 59.

- The passageway 120 may, as shown, be constantly open so as to provide continuous communication between the sound producing devices embodying the projector 119, and the air storage chamber 17. The other passageway 121 may be somewhat reduced in cross-section and the horn body is formed with a lateral recess intersecting the reduced portion of the passageway 121 within which recessed portion there is positioned a rotary valve 122 which may be in the form of a cylinder, and this valve has a diametrical passageway 123 which may be brought into alignment with the reduced portion of the passageway 121 to permit the free passage of air from the storage chamber 17 to the sound producing device embodying the projector 118, or may be moved out of alignment with said passageway to prevent such passage of air.
- 10 This valve may be actuated in any suitable manner, and for that purpose there is shown a rock-arm 124 secured to the outwardly projecting end of valve 122 and adapted to be manually actuated to rotate the valve as by 15 means of a wire, cord, or link 125 terminating at any desired point as somewhere near the normal position of the driver of the vehicle.
- 20 Normally, valve 122 will be held in one of its pre-determined positions, as for instance that shown in Figure 6 where it cuts off communication between the storage chamber and the sound producing device, as by means of a coil spring 126, one end of which may be 25 secured to the horn body 56 and the other end to the valve 122, and tensioned to maintain the valve in desired position.

A stop 127 is provided to limit actuation of the valve by the spring, and this stop may be 30 in the form of an arm 128 secured to the end wall —2— in any suitable manner, as by screws and carrying the flange or stop portion 127 lying in the path of movement of the lower projecting end of the rock-arm 124.

35 In this construction under normal conditions all of the air is supplied to one sound-producing device, and it is only necessary to rotate the valve 122, as for instance by the structure shown in order to permit a supply 40 of a proportionate amount of air to the other sound producing device for the production of two distinct notes.

Although we have shown and described 45 specific constructions of devices and details of form and arrangement of the same, we do not desire to restrict ourselves to the exact form, construction or arrangement of the sound producing devices, or to any particular number of such devices utilized, or to any 50 specific means for cutting off communication between one or more of said devices and the storage chamber, nor to the fact that one or more of said devices is normally cut off from communication with the storage chamber, as 55 the reverse may be true and the valve for cut-

ting off such communication may be normally open and adapted to be closed for causing the supply of all of the air to one of the said devices, as various changes and modifications may be made in each and all of said features without departing from the invention as set forth in the appended claims.

70 We claim:

75 1. A signaling device comprising a motor, a fluid compressor operated by said motor, a plurality of fluid resonant devices, means of communication between the fluid compressor and each of said fluid resonant devices, and means for cutting off communication between certain of the fluid resonant devices and the compressor with at least one of the fluid resonant devices remaining in constant communication with the fluid compressor.

80 2. A signaling device comprising a metallic horn body, a plurality of air resonant devices mounted on and secured to the horn body, said air resonant devices including projectors extending substantially parallel with each other outwardly from the horn body, a hollow casing secured to the horn body and extending forwardly therefrom in the space between two of said projectors, a magnetic coil disposed within said casing, an armature associated with said magnetic coil, a conduit system through the horn body for supplying air under pressure to said air resonant devices, a valve in said conduit system, an operating rod extending through said magnetic coil and connected to said armature for actuation thereby to unseat said valve when the magnetic coil is energized.

85 In witness whereof we have hereunto set our hands this 30th day of June, 1927.
